UNITED STATES PATENT OFFICE

2,640,189

OILTIGHT SWITCHBOARD PILOT LIGHT

Arthur B. Johnson, Jr., Maywood, Ill., assignor
to Furnas Electric Company, Batavia, Ill., a
corporation of Illinois

Application September 20, 1951, Serial No. 247,407

9 Claims. (Cl. 340—381)

1

The present invention relates generally to improvements in switchboard accessories, and relates more specifically to improvements in the construction of oiltight pilot light assemblies especially adapted for use on control station electric switchboards.

The primary object of my invention is to provide an improved electric pilot light assemblage which is simple and compact in construction and flexible in its adaptations.

It is frequently desirable when assembling a group of electric switches at a common control station, to include one or more pilot lights connected in its several electric circuits so as to clearly indicate the functioning thereof. In such stations it is also important that the switch units and the pilot lights be well protected against entry of foreign matter such as water and oil, and it is furthermore frequently desirable to employ different types of electric lamps in the pilot light units. In the prior switch board assemblies of this type, it was customary to utilize separate and relatively complicated means for sealingly clamping the lamp mounting base to the switch unit support and to likewise clamp the lamp lens to the base or its support; and it was also necessary in these prior control stations to provide special lamp mounting bases for each different type of lamp bulb which was employed thus further complicating the assemblies and making it difficult to properly set up the electric circuits.

It is therefore one important object of my present invention to provide an oiltight pilot light unit wherein a single member is utilized to sealingly clamp the lamp mounting base to the main switch support and to also likewise clamp the lamp lens to the same base.

Another important object of the present invention is to provide an electric pilot light assembly in which several different types of light bulbs may be interchangeably associated with a common base structure.

A further object of this invention is to provide an improved oiltight and convertible electric pilot light composed of few sturdy parts to produce a compact unit adapted to be readily assembled and installed within electrical circuits.

Still another object of the invention is to provide an improved electric pilot light assemblage capable of being quickly dismantled for the renewal of burned out light bulbs and for inspection of parts and attachment of terminals.

An additional object of my invention is to provide a pilot light unit especially adapted to be applied to an oiltight casing for supporting a

group of electric switches at a common control station, in a manner similar to the installation of the switch units.

A further object of this invention is to provide an improved electric pilot light unit which may be manufactured and sold at moderate cost for diverse uses, and which may be easily converted for use with either standard incandescent or neon light bulbs.

These and other objects and advantages of the invention will be apparent from the following detailed description, but the gist of the present improvement comprises the provision of an oiltight and convertible pilot light unit having a unitary lamp housing base with which different types of lamp bulbs may be interchangeably associated and caused to cooperate with a lens which is clamped to the base by the same means which clamps the base to a support so as to effect oil-tight sealing of the entire assemblage.

A clear conception of the improved features constituting the invention, and of the construction and mode of utilizing a typical convertible lamp unit embodying the same, may be had by referring to the drawing accompanying and forming a part of this specification wherein like reference characters designate the same or similar parts in the various views.

Fig. 1 is a side elevation of one of the improved pilot light units assembled for the reception of a standard neon light bulb;

Fig. 2 is a bottom view of the frame and contact assembly of Fig. 1, but with the lower retainer plate omitted;

Fig. 3 is a section through the pilot light assembly of Fig. 1, taken along the line 3—3;

Fig. 4 is a top view of the improved convertible pilot light unit, embodying either a neon or an incandescent lamp;

Fig. 5 is a side elevation of the same pilot light unit but assembled for the reception of a standard incandescent light bulb;

Fig. 6 is a bottom view of the frame and contact assembly of Fig. 5, with the lower retainer plate removed;

Fig. 7 is a section through the pilot light assembly of Fig. 5, taken along the line 7—7;

Fig. 8 is a bottom view of the lower retainer plate of the unit;

Fig. 9 is a side elevation of one of the improved lenses removed from the pilot light unit; and

Fig. 10 is a side view of the frame of the unit.

While the invention has been shown and described herein as having been embodied in a convertible pilot light unit adapted to interchange-

ably cooperate with only two different types of lamps and disposed in upright position, it is not my desire or intention to unnecessarily restrict the utility of the improved features or the disposition of the unit by virtue of this limited embodiment; and it is also contemplated that descriptive terms employed herein be given the broadest possible interpretation consistent with the disclosure.

Referring to the drawing, the improved pilot light unit shown therein, comprises in general a unitary frame or base 14 having a tubular upper portion 15 provided with external screw threads 16 and also having an integral flange 17 at the lower end of the portion 15; a reversible lamp retainer 18 detachably secured to the base flange and being cooperable with a lamp bulb 19 to maintain the same centrally within the tubular base portion 15; a dome shaped transparent lens 20 coating with the upper extremity of the tubular portion 15 through a sealing ring 21, and having thereon external screw threads 22 coextensive with the base threads 16; a support 23 embracing the base portion 15 and coaxing with the base flange 17 through a sealing gasket 24; a single clamping member or ring nut 25 cooperable with the screw threads 16, 22 to clamp the lens 20 against the base 14 and the latter against the support 23 through the ring 21 and gasket 24 respectively; a lower mounting plate 26 suspended from the base flange 17 by spacers 27; and terminals 28, 29 cooperable with contacts for electrically connecting the lamp bulb 19 into a circuit.

The frame or base 14 may be formed of a single piece of durable insulation and the tubular portion 15 should be carefully bored so as to clear the lamp bulb 19 as well as substitute bulbs of larger diameter. The bulb 19 of Figs. 1 to 3 is of the standard neon 110-220 volt type and has a metallic threaded supporting or plug end 31 adapted to be screwed into the sheet metal retainer 18 when positioned as shown in Fig. 3 so as to hold the lamp 19 in proper position; and the retainer 18 is detachably secured to the base flange 17 by means of two screws 32. The retainer 18 is electrically connected to the terminal screw 29 by a contact plate 33 and to a voltage dropping resistor 34 as illustrated in Fig. 2; and the light bulb 19 has an extreme end contact 35 which is insulated from the metallic screw threaded end 31 thereof and is connectible with the other terminal screw 28 by a second contact plate 36, both plates 33, 36 being attached to the base 14 by screws 37.

When a standard 110 volt incandescent lamp bulb 39 is to be interchangeably applied to the pilot light as in Figs. 5 to 7 inclusive, the retainer 18 must be reversed as indicated in Fig. 7 in order to accommodate the larger incandescent bulb 39. A resistor 40 must also be provided for voltages greater than 110 volt, and this resistor may be inserted between the retainer 18 and plate 33 and is fastened to the base flange 17 by a screw 41 coaxing with an opening 42 as shown in Figs. 2 and 6. In this alternative assemblage, the contact plate 36 which engages the lamp contact 35, is connected to the terminal screw 29; but the retainer 18, contact plates 33, 36, and terminal and attaching screws 28, 29, 37 are all of similar construction so that only a few parts must be provided when making the conversion.

The dome shaped lens 20 may be formed of any suitable transparent material such as glass

or plastic, and besides being provided with the screw threads 22, this lens has a lower portion 44 of reduced diameter adapted to snugly engage a counterbore in the tubular base portion 15 and which is surrounded by the sealing ring 21. The ring 21 may be formed of rubber or rubber composition, and the sealing gasket 24 which is interposed between the base flange 17 and the support 23 is also formed of similar material and embraces the tubular base portion 15. A pin 45 may be provided between the base flange 17 and a hole in the support 23 in order to properly position the pilot light assemblage and the gasket 24, and an indicating plate 46 may also be applied to the support 23 around the base portion 15. The ring nut 25 has peripheral serrations or lugs as shown in Fig. 4 for facilitating manipulation thereof, and this single nut 25 besides clamping the lens 20 to the base 14 and the latter to the support 23, compresses the sealing ring 21 and gasket 24 and also holds the plate 46 in place.

The lower mounting plate 26 which is suspended from the base flange 17 by means of the spacers 27, is secured to these spacers by screws 47 and has one or more peripherally recessed projections 49 riveted or otherwise attached thereto. These projections 49 serve to hold the pilot light unit in position within a casing preparatory to final application of the support 23 which serves as the cover of the casing, and before the ring nut 25 has been applied to the screw threads 16 to finally clamp the pilot light assemblage to the support. The lens 20, base 14, clamping nut 25, spacers 27, and mounting plate 26 may be utilized without alteration for cooperation with either type of pilot lamp 19, 39, and the electrical connections may be applied to the terminal screws 28, 29 while the pilot light unit is being held solely by the lower plate projections 49.

When the various parts of the improved unit have been properly constructed and assembled as above described, so as to accommodate either a neon or an incandescent lamp bulb, the lower plate 26 will be rigidly suspended from the base 14 and the lamp bulb may be firmly positioned within the retainer 18 before the lens 20 is attached to the base 14. After the lamp has been inserted, the sealing ring 21 should be applied about the lens projections 44 and the clamping nut 25 should be screwed upon the lens threads 22 to firmly unite the lens and ring nut. The lower plate 26 may then be properly positioned within a receiving receptacle or casing and temporarily held with the aid of the plate projections 49 and the electrical conductors should be attached to the terminal screws 28, 29, whereupon the cover support 23 and the indicating plate 46 may be slipped over the tubular base portion 15 and caused to coat with the gasket 24 and pin 45. The ring nut 25 may then be finally applied to the threads 16 of the projection 15 to firmly clamp the unit against the support 23 and to compress the ring 21 and gasket 24 into oil-tight sealing engagement with the adjacent parts.

From the foregoing detailed description, it will be apparent that the present invention provides a pilot light unit which is simple and compact in construction and which may be readily converted for interchangeable use with several types of lamps either by the manufacturer or by the user. The single ring nut 25 serves the dual purpose of providing an effective oiltight seal both between the base 14 and the lens 20 and between the cover support 23 and the base 14; and only a few simple

and inexpensive parts are required in order to effect conversion of the unit for use with either type of lamp bulb 19, 39. The various parts of the improved unit are conveniently accessible for inspection, installation, and renewal of lamp bulbs, but are thoroughly protected during normal use, and these pilot light assemblages may be utilized either singly or in conjunction with various types of switches associated with a common support at control stations adapted for diverse purposes.

It should be understood that it is not desired to limit this invention to the exact details of construction or to the precise usage of the pilot light units herein shown and described, for various modifications within the scope of the appended claims may occur to persons skilled in the art.

I claim:

1. In an oiltight pilot light, a lamp housing base formed of insulation and, a support for said base, a lens cooperable with an electric lamp confined within said base, separate sealing gaskets interposed between said base and said support and lens, and a common member for sealably clamping one of said gaskets between said base and said support and another between said lens and said base.

2. In an oiltight pilot light, a lamp housing base formed of insulation and having external screw threads, a support for said base, a lens cooperable with an electric lamp confined within said base and also having external screw threads, flexible sealing elements interposed between said base and said support and lens, and a common internally threaded member coacting with said elements and said external base and lens threads to sealingly clamp the base to said support and the lens to the base.

3. In an oiltight pilot light, a lamp housing base formed of insulation, a support for said base, a lens cooperable with various types of electric lamps confined within said base, a reversible lamp retainer for interchangeably supporting various types of lamps within said base and said lens, and a common member for sealably clamping said base to said support and said lens to said base.

4. In an oiltight pilot light, a lamp housing base formed of insulation and having external screw threads, a support for said base, a lens cooperable with neon or incandescent electric lamps confined within said base and also having external screw threads, a reversible lamp retainer for interchangeably supporting either of said types of lamps within said base and said lens, flexible sealing elements interposed between said base and said support and lens, and a common internally threaded member coacting with said elements and said external base and lens threads to sealingly clamp the base to said support and the lens to the base.

5. In an oiltight pilot light, a lamp housing base formed of insulation and having an integral flange and a centrally bored tubular portion provided with external screw threads extending away from said flange, a support for said base having

said flange on one side thereof and said screw threads projecting beyond its opposite side, a lens cooperable with an electric lamp confined within said base and also having external screw threads coextensive with said base threads, flexible sealing elements interposed between said lens and base and support, and a ring nut coacting with said base and lens threads to simultaneously clamp said elements in place.

10 6. In an oiltight pilot light, a lamp housing base formed of insulation, a support for said base, a lens cooperable with an electric lamp confined within said base, sealing elements between said base and said support and lens, a common member for sealably clamping said elements and said base to said support and said lens to said base, and means for holding said base in a predetermined position prior to application of said clamping member.

20 7. In an oiltight pilot light, a base formed of insulation and having an externally threaded tubular portion and an integral external flange at one end thereof, a lamp bulb retainer secured to said flange, a lens coacting with the opposite end of said tubular portion, a support embracing said tubular portion adjacent to said flange, flexible sealing elements interposed between said flange and support and between said lens and said tubular portion, and a single ring nut co-acting with the threads of said tubular portion to clamp said elements between the adjacent parts.

25 8. In an oiltight pilot light, a base formed of insulation and having an externally threaded tubular portion and an integral external flange at one end thereof, a lamp bulb retainer secured to said flange, a lens coacting with the opposite end of said tubular portion, a support embracing said tubular portion adjacent to said flange, means suspended from said flange for holding said base in a predetermined position before said support is applied thereto, and a single ring nut cooperable with the threads of said tubular portion to clamp said lens to said base and said base to said support.

30 40 9. In an oiltight pilot light, a base formed of insulation and having an externally threaded tubular portion and an integral external flange at one end thereof, a lamp bulb retainer secured to said flange, a lens coacting with the opposite end of said tubular portion, a support embracing said tubular portion adjacent to said flange, means cooperable with the threads of said tubular portion to clamp said lens to said base and said base to said support, and means cooperable with said flange and said retainer for interchangeably accommodating electric lamp bulbs of different types.
